UNITED STATES PATENT OFFICE

100,701

DESIGN FOR A HEATING STOVE

Henry Lange, Quincy, Ill., assignor to Quincy Stove Manufacturing Company, Quincy, Ill.

Application December 2, 1935, Serial No. 59,868

Term of patent 7 years

To whom it may concern:

Be it known that I, Henry Lange, a citizen of the United States and a resident of the city of Quincy, county of Adams, and State of Illinois, have invented a new, original, and ornamental Design for a Heating Stove, of which the following is the specification, reference being had to the accompanying drawing, forming a part thereof;

Fig. 1 is a perspective view of a heating stove
showing my new design;

Fig. 2 is a front view thereof shown on a slightly smaller scale than Fig. 1;

Fig. 3 is an end view thereof shown on a slightly smaller scale than Fig. 1.

I claim:

The ornamental design for a heating stove,
as shown.

HENRY LANGE.
